UNITED STATES PATENT OFFICE.

IVY DAPHENE HOWELL, OF BALLSTON SPA, NEW YORK.

DESIGN FOR A DIRECTION-INDICATOR.

57,910.

Specification for Design.

Patented May 17, 1921.

Application filed August 6, 1920. Serial No. 401,800. Term of patent 14 years.

To all whom it may concern:

Be it known that I, Ivy D. Howell, a citizen of the United States, and a resident of Ballston Spa, in the county of Saratoga and State of New York, United States of America, have invented a new, original, and ornamental Design for a Direction-Indicator, of which the following is a specification.

Reference is to be had to the accompanying drawing, forming a part of the same showing my design as adapted to a direction indicator for toilet service adapted to be posted or hung in public places as a guide to such service.

The figure is a face view of a direction indicator embodying my new design.

The design is arranged in disk form with sectorial divisions of contrasting color emanating from two semicircles bearing sex designations, the large sector of color bearing the words "Universal comfort service."

I claim:

The ornamental design for a direction indicator substantially as shown and described.

IVY DAPHENE HOWELL.
